(57) **CLAIM**

The ornamental design for a portable electronic device stand, as shown and described.

DESCRIPTION

FIG. 1 is a first, top perspective view of a portable electronic device stand embodying our new design, illustrated in a first configuration;

FIG. 2 is a second, top perspective view thereof;

FIG. 3 is a bottom perspective view thereof;

FIG. 4 is an enlarged detail view of a portion of FIG. 3;

FIG. 5 is a front view thereof;

FIG. 6 is a back view thereof;

FIG. 7 is a left side view thereof;

FIG. 8 is a right side view thereof;

FIG. 9 is a top view thereof; and

FIG. 10 is a bottom view thereof.

FIG. 11 is a first, top perspective view of the portable electronic device stand embodying the new design, illustrated in a second configuration;

FIG. 12 is a second, top perspective view thereof;

FIG. 13 is a bottom perspective view thereof;

FIG. 14 is an enlarged detail view of a portion of FIG. 13;

FIG. 15 is a front view thereof;

FIG. 16 is a back view thereof;

FIG. 17 is a left side view thereof;

FIG. 18 is a right side view thereof;

FIG. 19 is a top view thereof; and,

FIG. 20 is a bottom view thereof.

The dot-dash broken lines in FIGS. 3, 4, 13, and 14 form the boundaries of the enlarged detail views and form no part of the claimed design.

1 Claim, 20 Drawing Sheets
